Harry D. Wallace

ATTORNEY.

UNITED STATES PATENT OFFICE.

STEPHEN H. GALLAGHER, OF SYRACUSE, NEW YORK.

KNIFE-SHARPENER.

1,352,888.

Specification of Letters Patent. Patented Sept. 14, 1920.

Application filed September 16, 1919. Serial No. 324,062.

To all whom it may concern:

Be it known that I, STEPHEN H. GALLAGHER, a citizen of the United States, residing at Syracuse, in the county of Onondaga and State of New York, have invented certain new and useful Improvements in Knife-Sharpeners, of which the following is a specification.

This invention relates to improvements in knife sharpeners, designed particularly for use by butchers, butlers and the like, for sharpening carving and other knives.

The invention consists of cutting a number of corresponding longitudinal grooves in the blades of the common butchers' steels, and then filling the said grooves with an abrasive element, over which knives and like instruments may be drawn frictionally during the whetting operations, for effecting a more rapid sharpening of said instruments than is possible by the use of the steel alone. A particular object of the invention is to provide novel and simple means for abrading, as well as smoothing and finishing the cutting edges of the instruments, by the employment of a single sharpening tool, thereby obviating the necessity of first grinding, and then whetting the same, in order to produce a keen cutting edge.

I attain these objects by the means set forth in the detailed description which follows, and as illustrated by the accompanying drawing, in which—

Figure 1 is a side view of the complete device; showing the location and arrangement on one of the inlaid abrasives.

Fig. 2 is an edge view of the same.

Fig. 3 is a vertical cross-section, taken on line 3—3 of Fig. 1.

Fig. 4 is a similar sectional view; showing a slight modification of the device.

Fig. 5 illustrates still another modification.

In the drawing, 2 is the blade of the sharpener, which is preferably made of steel, similar to the well-known butchers' and meat-cutters' steels, and having at one end a tine 3, which may be driven tightly into a handle 4. 5 is a guard or hilt which is disposed between the handle and the blade 2, to prevent injury to the hand that holds the device during the sharpening operations. The blade 2 is preferably tapering from the guard toward its free end, as shown, for

giving greater strength, as well as for increasing the whetting surface.

My improvement consists of providing two or more corresponding longitudinal surface grooves or recesses, as 6, preferably sunk in the opposite sides of the blade 2, and then filling the said grooves with any suitable abrasive 7, such as alundum, carbondum, emery and the like. The abrasive is first made up in plastic state and then applied to the grooves until the latter are entirely filled. The abrasive is preferably mixed with a suitable water-proof cement which causes it to adhere to the walls of the grooves and renders it impervious to water, and when the abrasive becomes dry and hard, it is ready for use. The grooves 6 are preferably made deep enough to hold sufficient amount of the abrasive to last through the lifetime of the steel. By constructing the grooves 6 substantially semi-circular in cross-section, the margins of the abrasive are protected by the steel against injury due to rough handling, and furthermore the abrasive is not liable to be broken or displaced.

In practice, the operator holds the steel by one hand in such manner that when a knife is alternately brought into contact with the opposite sides of the blade 2, the cutting edge of the knife makes a fair frictional engagement with the abrasive 7. The abrasive naturally wears the metal of the knife away more rapidly than the steel, and accordingly leaves the cutting edge of the knife somewhat ragged. The abrasive 7 is so positioned, however, that during the ending of each stroke of the knife across the blade 2, the knife is only in contact with the steel, which reduces the roughness and raggedness and leaves the edge of the knife substantially smooth and keen.

In Fig. 4 I have shown a round blade 2', in which the abrasive material 7' is preferably crowned at its exposed surface corresponding to the curvature of the blade 2'. In order to smooth the cutting edge of the knife after it has been abraded by being drawn over the material 7', the operator should give the blade 2' a slight turn in either direction, so as to bring the knife into fair contact with the plain steel.

Fig. 5 illustrates still another modification, in which the blade 2'' is provided with

curved grooves 6^a, on its opposite flattened sides, in which the abrasive material 7^a is disposed, and the latter is preferably arranged so that its exposed surfaces have the same crown or curvature as the body of the blade. By this construction and arrangement, the corresponding top and bottom abrasives are brought nearer to the lateral edges of the blade, and by providing two 10 grooves 6^a on each side of the blade, it is more serviceable for both right and left handed operators.

Having thus described my invention, what I claim as new and desire to secure by Letters Patent, is—

1. A knife sharpener, comprising an elongated steel blade having a plurality of longitudinal grooves, and an abrasive inlaid in said grooves adapted to be frictionally engaged by a knife when the latter is drawn across said grooves.

2. A knife sharpener comprising a tapering oval blade having a tine at one end, and having in its opposite sides similar tapering longitudinal grooves, a plastic

abrasive filling and adhering to said grooves, and a handle supported by said tine.

3. A knife sharpener comprising a tapering metal blade having corresponding longitudinal grooves, and an abrasive element filling and adhering to the walls of said grooves, the exposed surfaces of said abrasive being slightly crowned and being substantially flush with the metal at the 30 margins of said grooves.

4. A knife sharpener, comprising a tapering metal blade having a plurality of elongated surface grooves, and an abrasive material disposed in and filling said grooves, 40 the said material at its exposed surfaces being substantially flush with the metal at all of its margins, whereby the cutting edge of a knife is first roughly abraded by contact with said material, and finally rendered 45 smooth and keen by its subsequent contact with the metal of the blade adjacent said margins.

In testimony whereof I affix my signature.
STEPHEN H. GALLAGHER.
